Filed Oct. 29, 1962, Ser. No. 233,604
4 Claims. (Cl. 112—252)

The present invention relates generally to improvements in sewing machines, and it relates in particular to an improved thread cutting mechanism employed in combination with a sewing machine.

In machine sewing operations, particularly in the commercial mass production of garments or the like, it has been the conventional practice to successively sew successive similar panels or work pieces. These successive panels, as they emerge from the sewing machine head, carry trailing chains of stitches which are either cut with the emergence of each work piece or are permitted to be joined to the next successive work pieces and are subsequently cut prior to the next operation on the particular work piece. In either case, the work piece separating procedure is inconvenient and time-consuming and thereby increases the cost of the end product. Various types of sewing machine thread cutters, both of the automatic and hand operated type, have been employed and proposed but these possess numerous drawbacks and disadvantages. The hand operated thread cutters offer little advantage over the manual cutting of the thread, whereas the automatic thread cutters are complex mechanisms whose general operation leave much to be desired. In addition to their other drawbacks, the automatic thread cutters heretofore available frequently left long thread tails on the work pieces which are highly undesirable and are generally to be avoided.

It is, therefore, a principal object of the present invention to provide an improved sewing machine.

Another object of the present invention is to provide an improved automatic thread cutter for sewing machines.

Still another object of the present invention is to provide, in a sewing machine, an improved mechanism for cutting the threads between successive work pieces in a neat and trim manner.

A further object of the present invention is to provide a thread cutting mechanism of the above nature characterized by its simplicity, ruggedness, reliability and versatility.

The above and other objects of the present invention will become apparent from a reading of the following description, taken in conjunction with the accompanying drawings, wherein

FIGURE 1 is a top plan fragmentary view of a preferred embodiment of the present invention;

FIGURE 2 is an enlarged sectional view taken along line 2—2 of FIGURE 1;

FIGURE 3 is an enlarged sectional view taken along line 3—3 of FIGURE 1, the thread cutting element being illustrated in its advanced position;

FIGURE 4 is a view similar to FIGURE 3, the thread cutting element being illustrated in its retracted position;

FIGURE 5 is a sectional view taken along line 5—5 of FIGURE 3;

FIGURE 6 is a sectional view taken along line 6—6 of FIGURE 4; and

FIGURE 7 is a diagrammatic view illustrating the stroke of the cutting element relative to the successive work pieces.

In a sense, the present invention contemplates the provision, in combination with a sewing machine including means for advancing a work piece along a predeter-

mined path past a sewing needle, of a thread cutting member movable between an advanced and a retracted position across said path forward of said needle, and means responsive to the presence and absence of said work piece at a predetermined point urging said cutting member alternatively respectively to said advanced and retracted positions.

According to a preferred form of the present mechanism, the thread cutting member is defined by a hot wire electrical resistance element the ends of which are connected to corresponding of a pair of parallel metal bars separated by a sandwiched sheet of insulating material and joined to form an assembled arm which is pivotally supported below the work piece path. The bars are connected to a source of low voltage current. A sensing element is defined by a pivoted arm swingable in a vertical plane in the vicinity of the sewing machine foot piece, the foot piece carrying a laterally spaced arm which restricts the vertical movement of the work piece in the sensing area, the sensing element registering with a space between the foot piece and the laterally spaced arm. The pivoted sensing arm engages the cutting member supporting arm to retract the latter when the sensing arm is depressed and the cutting member arm is gravity urged to its advanced position normally to urge the sensing arm to its raised advanced position. A suction pipe is provided having an opening forward of and directed toward the retracted cutting member.

Referring now to the drawing and particularly to FIGURES 1 to 7 thereof, which illustrate a preferred embodiment of the present invention, reference numeral 10 generally designates a reciprocating needle bar of a conventional sewing machine which releasably engages a sewing needle 11 in the usual manner. The sewing machine includes an L-shaped throat plate 12 secured to and extending laterally from the machine base plate 13, and provided with an inner transverse edge 14 confronting and spaced from the end edge of base plate 13 to define therewith a longitudinally extending recess 16. Formed in throat plate 12 are a pair of laterally spaced slots having the usual reciprocating feed dogs 17 registering therewith and a needle receiving opening.

A foot piece 18, having a curved front upwardly curved end 19, is located in vertical alignment with throat plate 12 and is supported by a bracket arm 19 at its rear end. Bracket arm 19 and foot piece 18 are selectively movable between a raised position and a depressed position in engagement with feed dogs 17 in the usual manner, and the foot piece 18 has a needle registering opening formed therein. In order to restrict the vertical movement of the work piece in the sensing area, there is provided a guide arm 20 extending along the length of the opening 16 and substantially coplanar with the underface of foot piece 18. Guide arm 20 registers with opening 16 and is laterally spaced from edge 14 of the throat plate to delineate therebetween a sensing area.

A bracket assembly 21 is positioned under base plate 13 and includes an upper transversely extending plate 22 affixed to the underface of base plate 13 by screws 23. Depending from plate 22 intermediate the ends thereof is a first bracket plate 24, and depending from the leading end of plate 22 is a second bracket plate 26 adjacent to the leading end of throat plate 12. A pivot screw 27 engages a tapped bore in bracket plate 26 and is rotatably engaged by a block 28 which is sandwiched between the head of screw 27 and a spacer 29 engaging screw 27.

A cutter lever assembly 30 is mounted on block 28, rockable therewith, and is formed of a pair of electrically conducting upper and lower metal bars 32 and 33 respectively, separated by an intermediate substantially coextensive band 34 of suitable insulating material. Bands 32,

33 and 34 are mutually secured by screws 36 engaged by insulating sleeves 37 and opposite insulating washers to separate electrically the bars 32 and 33. Bar 33 is grounded through block 27 and by way of a flexible lead 38, and bar 32 is connected by a flexible lead 39 to a terminal of a high current low voltage source, the other terminal of which is grounded. The voltage source may be the secondary of a step-down transformer, the primary of which is connected to the standard A.C. power line.

10 Mounted at the end of lever 30 is a cutting element 40 formed of a U-shaped metal rod having a constricted looped end section 41, the opposite legs 42 of the cutting element 40 being firmly connected to the ends of the conductor bars 32 and 33 respectively (see FIGURE 3). The resistance of element 40 is greater than that of bars 32 and 33 so that the resistance heating is primarily confined to element 40 which reaches a temperature which will readily burn and sever the conventional sewing threads and fuse those of a thermoplastic nature. The weight of cutter assembly 30 is so distributed and the assembly is so pivoted that it is urged by gravity to swing counter-clockwise, as seen in FIGURE 3, to urge cutting element 40 to its topmost position. The path of the cutting element 41 is across the path of the work piece and the horizontal axis of the stitching, so that the upward or downward stroke of the cutting element 40 effects the severing of any thread, such as a chain of stitching, which is delivered by the sewing machines and carried forwardly. The cutting element 40 is limited in movement to its advanced or raised position, as illustrated in FIGURE 3, and to its depressed or retracted position, as illustrated in FIGURE 4, by an angulated member having one arm 43 affixed to the underface of pivoted block 28 and another arm 44 swingable with the lever assembly 30 into engagement with spaced opposing abutments 46 and 47 respectively.

Pivoted to bracket plate 24 by means of a pin 48 is a sensing member-defining fork 49 having an upper leg 50 registering with elongated opening 16. The lower edge of leg 50 engages the upper surface of bar 32 adjacent the cutting element 40 and the upper edge of the leg 50 is upwardly convex. Fork member 50, cutter assembly 30 and the path of the work piece as advanced by the sewing machine are so related that in the absence of a work piece over opening 16 the sensing member 49 is swung clockwise to its raised position, as illustrated in FIGURE 5, by the swinging of the lever assembly 30 to its raised position, and the movement of a work piece into registry with opening 16 swings sensing member 49 to its depressed position as seen in FIGURE 6, leg 50 in turn bearing upon and depressing the lever assembly 30.

A suction conduit 51, which is connected to a source of negative pressure, is positioned beneath and along the base plate 13 and terminates in a rearwardly directed intake opening 52 confronting the plane of movement of the cutting element 40 immediately below the stitching line.

The sewing machine described above is employed in the usual manner. Prior to the sewing operation, the current circuit to the cutting member 40 is closed to bring it to operating temperature. Cutting member 40, lever assembly 30 and the sensing member 49 are initially in their raised positions. A work piece W is fed to the sewing machine and the sewing machine is actuated. The work piece W is advanced by feed dogs 17 and stitching applied thereto. The advancing work piece W travels across opening 16 to engage and depress sensing member 49 which in turn depresses lever assembly 30 and cutting member 40 below the level of the work piece. When the end of the work piece W passes the sewing needle, it carries with it a trailing tail or chain of thread or stitches, and as the trailing edge of the work piece W passes the sensing member 49

it is released for upward movement, permitting lever assembly 30 and sensing member 49 to swing to their raised positions. The rising cutting member 40 severs the chain L adjacent the trailing edge of work piece W and where the thread is thermoplastic, it fuses and seals the chain ends. The tail L, which is attached to the next successive work piece W, is drawn toward and into the suction conduit 51. As the leading edge of the next successive work piece W travels across space 16, it depresses sensing member 49 which in turn depresses lever assembly 30 and cutting member 40 to sever the stitch tail L immediately forward of the work piece leading edge and the severed tail L is completely drawn into the suction conduit 51.

15 While there has been described and illustrated a preferred embodiment of the present invention, it is apparent that numerous alterations, omissions and additions may be made without departing from the spirit thereof.

What is claimed and desired to be secured by Letters Patent is:

20 1. In combination with a sewing machine including a sewing needle and means for advancing a work piece along a predetermined path past said sewing needle, a pivotally mounted arm swingable between a raised and a depressed position and means normally urging said arm to said raised position, an electrically heated hot wire cutting element mounted on and extending beyond said arm and swingable with said arm between a raised and a depressed position across said work piece path forward of said needle, and a pivotally mounted actuating member 25 including a cam surface along its upper edge disposed along the path of said work piece and movable with said actuating member between a raised and a depressed position, said actuating member further including an under-surface registering with the upper surface of said arm 30 whereby said actuating member is normally held in its raised position by said arm and said urging means and movable to said depressed position when said cam surface is depressed by engagement with a work piece passing thereover to thereby effect a movement of said arm and 35 said cutting element between said raised and depressed positions in response to the respective raising and depression of said actuating member to thereby cut threads positioned in the path of said cutting element on either the upstroke or downstroke of said cutting element.

40 2. The combination of claim 1 including means restricting the movement of said work piece across the path of movement of said actuating member.

45 3. The combination of claim 1 including a member counterbalancing said arm normally to urge said cutting element toward its raised position.

50 4. The combination of claim 1 including a suction means located adjacent to said path of said cutting element.
